UNITED STATES PATENT OFFICE.

ALBERT L. HELLER, OF CHICAGO, ILLINOIS.

DISPLAY CABINET.

Application filed May 22, 1922. Serial No. 562,597.

To all whom it may concern:

Be it known that I, ALBERT L. HELLER, a citizen of the United States, residing at Chicago, in the county of Cook and State of Illinois, have invented a certain new and useful Improvement in Display Cabinets, of which the following is a full, clear, concise, and exact description, reference being had to the accompanying drawings, forming a part of this specification.

My invention relates to the art of exhibiting, and more specifically to improved means for displaying articles for sale, facilitating the sale and saving time and money in handling and merchandising these articles.

One object of my invention is to enhance the attractive appearance of trinkets or small articles of jewelry, intended to be sold individually or in individual sets, when placed on display.

Another object is to save time of salesman in inserting the articles for display, or removing them when making a sale.

Another object is to conserve showroom space in making display and still display articles effectively, protect them from exposure to dirt and dust and reduce the likelihood of pilfering the articles.

Another object is to provide a display device from which the articles may be removed without soiling in handling or disfiguring the device.

Another object is to provide supporting and displaying means of equal attractiveness with the articles themselves.

Another object is to provide a combined shipping container and support having sufficient rigidity for safe shipping, a sufficiently attractive appearance for effective display of the articles, and a sufficiently low cost to permit the articles to be sold at a reasonable price.

Another object is to support a plurality of articles in symmetrical arrangement with their median planes all in the median plane of the support and container, so that the container may be opened and placed on exhibition without any re-arrangement.

Another object is to provide a display container having an individual insert for each individual article or set of articles, each individual insert bearing the price of the article supported thereby, so that articles of several different prices can be exhibited in

the same container without confusion. This materially extends the range of articles which may be effectively displayed in a single device of moderate size.

Other objects and advantages of my invention will become apparent as the description proceeds.

In the accompanying drawings:

Fig. 1 is a perspective view of a device according to my invention; 65

Fig. 2 is an enlarged perspective of the same device;

Fig. 3 is a detailed perspective showing the individual cells;

Fig. 4 is a detailed view of the individual 70 holder;

Fig. 5 is a similar view of a modified holder.

In the embodiment of my invention selected for illustration, side walls 10, an end wall 12, and a bottom 14, (preferably, but not necessarily all of opaque material), co-operate with a transparent cover 16 to define a box-like enclosure open at the rear. The top 16 preferably slopes downward and 80 forward.

One or more drawers 20 (in this instance two), are inserted from the rear to hold the display containers 22 in position. These drawers are provided with false bottoms 24 85 inclined parallel to top 16, the edge of the drawers projecting above the false bottom on all sides so that the containers will be held by the drawers for insertion and removal. Obviously, any number of drawers 90 may be employed. The box, or case, and drawers are permanent equipment retained by the dealer, while the container is designed for shipping as well as for exhibition purposes, and may be discarded when the articles are sold; although, of course, in some instances, it may be desirable to return it for re-filling.

The container 22 comprises a simple box of cardboard or similar material, subdivided 100 by a lattice structure into a plurality of individual compartments 26. The walls 28 of the lattice terminate in a plane lying below the plane of the top of the container 22. In the embodiment disclosed, the lattice is formed by nesting a plurality of small boxes in a large container, permanently attached to the body of the container, so that the dividing walls of the lattice are double, and the assembled structure has a 110

double bottom. The small boxes may be loose, but I prefer to glue them in place to prevent displacement. In spite of the apparent waste of material involved, this type of construction is cheaper in small sizes, on account of the uniformity of the parts, and the ease and simplicity of assembling the same. It will be obvious, however, that in its other aspects, my invention is not limited to the particular type of lattice construction disclosed.

The individual article supports each comprise a central rectangular portion 30, and two end flaps 32 bent down to enter the compartment 26, and of substantially equal height with the walls 28 of the lattice, so that central portion 30 is held substantially flush with the top of the lattice. In this way, the pressure exerted by the flaps 32 against the lattice structure acts in a way to hold the article supports more firmly in place. The line of joining flaps 32 to the body 30 may be perforated so that the flaps may, if desired, be removed after the card and article are removed from the container.

The portion 30 is preferably perforated or slit at one or more points, in this instance two, to receive and support one or more articles, those illustrated being cuff-links made in two detachable parts. Each insert carries at the upper edge of portion 30, a trademark or some distinctive identification of the article carried by the insert. Near the lower edge of portion 30, each insert carries indicia indicating the price of the particular individual article or set of articles carried by the insert.

On one of the flaps 32, preferably the front one, indicia are placed, identifying the manufacturer, wholesaler or retailer of the goods. These indicia are concealed when the goods are on display, but are exposed by withdrawing the insert for detailed inspection or delivery of the goods. This inconspicuous way of identifying the origin of the product, without any conspicuous advertising of such origin, is out of the ordinary, and creates a favorable impression in the mind of the customer or prospective customer.

A considerably stiffer support for the article may be provided by forming side flaps 36 on the body 30 as well as end flaps 32. Alternatively, box 22 may be filled with article supports according to Figure 5, without providing any lattice structure to hold them.

The problem of suitably supporting the particular type of button illustrated in the drawings has heretofore been a rather troublesome one. They are too high, when assembled, to stand firmly on one end, and when the entire button is in plain view they are not of very attractive proportions. This is immaterial as far as the use of the

button goes, but presents a difficulty in making an attractive display of them. It will be seen that compartments 26 only house or contain half the button, and that the housed half is concealed. Then by fastening this elementary container and support in another, large enough to house the entire button, a suitable shipping container is obtained.

Without further elaboration, the foregoing will so fully explain the gist of my invention, that others may, by applying current knowledge, readily adapt the same for use under various conditions of service. It will, for instance, be obvious that article supports as shown in Fig. 4 could be put in a lattice having parallel walls running in one direction only, while those shown in Fig. 5 need no lattice at all. Many alterations and modifications may be made without eliminating certain features which may properly be said to constitute the essential items of novelty involved, which items are intended to be defined and secured to me by the following claims.

I claim:

1. In combination, a base, a lattice for supporting engagement with a plurality of inserts on a plane spaced from said base, and inserts having end portions bent down to pass below the plane of support and offering frictional resistance to withdrawal.

2. In combination, a base, a lattice for supporting engagement with a plurality of inserts on a plane spaced from said base, and inserts having end portions bent down to pass below the plane of support and offering frictional resistance to withdrawal, each insert having positive abutment with its supporting means to prevent displacement downwardly.

3. In a device for displaying two-part cuff buttons, a shallow tray of a depth substantially the height of the button to be displayed, partitions in said tray, the tops of said partitions extending above the bottom of the tray a distance substantially equal to the height of one part of said two-part button, and a mounting card having a perforation through which the parts of a button are connected together, said card having depending flanges of substantially the depth of the lower half of a button, said flanges being adapted to engage adjacent partitions and rest against the bottom of the tray for holding the card and attached button in place in the tray.

4. In a device for displaying two-part cuff buttons, a shallow tray of a depth substantially the height of the button to be displayed, a lattice structure in said tray spaced above the bottom of the tray by substantially the height of one part of said two-part button, and a mounting card having a perforation through which the parts

- of the button are connected together, said card having the ends bent down to provide positive abutment with its support to limit downward movement and frictional engagement with the lattice to resist withdrawal.
5. In combination, a horizontal tray having parallel partitions disposed below the top of the tray and an article support comprising a flat rectangular body portion having a perforation therethrough, depending flaps formed along the margins of the body portion by bending at substantially right angles integral portions of the stock of which the body portion is composed, said flaps having inherent resiliency for engaging the partitions to hold the article support in place in the tray, said body portion alone holding the article against displacement in any direction.
- 10 6. In combination, a mounting comprising a body portion formed of cardboard, said body portion having a pair of perforations, a pair of two-part cuff buttons secured together through said perforations, said body portion having integral depending flanges extending downward to house the lower halves of the buttons, and a main support for supporting a plurality of said mountings, said main support having individual supporting means, each co-operating with and engaged by the flanges of a mounting for displaying a plurality of pairs of cuff buttons.
- 15 7. In combination, a shallow tray having a flat bottom and sidewalls along its edges terminating in a plane substantially parallel to the bottom, means lying below the plane of the top edges of said sidewalls for forming a plurality of pockets in said tray, a supporting card, an article to be displayed secured to said card partly on one side and partly on the other side of said card, said card having resilient depending flanges formed by bending down opposite edges of the card, said flanges being adapted to enter said pocket and to hold the card below the top of the sidewalls of the tray by engagement with the sides of said pocket.
- 20 8. In combination, a display holder for a two-part article comprising a card having a perforation through which both parts of the article are connected together and connected to the card, one part on one side and another part on the opposite side, said card having depending flanges extending down below the adjacent part of the article being displayed, said flanges being formed by bending down opposite margins of the card, and means for nesting a plurality of said cards together in proximity, said means comprising a supporting tray having a plurality of pockets.
- 25 9. In combination, a display holder for a two-part article comprising a card having a perforation through which both parts of the article are connected together and fastened on the card, one part on one side and another part on the opposite side, said card having downwardly extending flanges on opposite margins, and means for nesting a plurality of said cards together in proximity, said means comprising a supporting tray having a lattice structure, the individual apertures in said lattice structure receiving the individual cards.
- 30 10. In combination, a display holder for a two-part article comprising a card having a relatively small perforation therethrough through which perforation both parts of the article are connected together and connected to the card, one part on one side and another part on the opposite side, said card having depending flanges extending down below the adjacent part of the article being displayed, said flanges being formed by bending down opposite margins of the card, and means for supporting a plurality of said cards in close proximity to each other, said means comprising a frame providing two sets of parallel partitions crossing each other at substantially right angles.
- 35 11. In combination, a card for supporting an article of jewelry, comprising a body portion with depending flanges, and a tray for supporting a plurality of said cards, said tray having pockets adapted to be engaged by and to grip the depending flanges for holding the cards upon the tray.
- 40 12. In combination, a two-part article and a support therefor comprising a card having an aperture through which the parts of the article are connected together, said card having depending flanges extending below the adjacent part of the article and forming supporting means for the card and the article, said card having adjacent the article indicia relating to the article, and having printed on the same side of the card but upon the depending flange, indicia identifying the seller of the article, and a tray having a series of partitions, the depending flanges of said card and the adjacent part of the article being adapted to enter and be held in said tray between partitions, said partitions concealing said latter indicia.
- 45 13. In witness whereof, I hereunto subscribe my name this 19th day of May, 1922.
- 50 14. ALBERT L. HELLER.
